APPARATUS AND METHOD FOR PREPARING
CONCRETE IN MIXERS

Robert B. Gage, Trenton, N. J., assignor of one-half to Robert W. Baily, Philadelphia, Pa.

Application December 14, 1932, Serial No. 647,106

8 Claims. (Cl. 83—73)

An object of my present invention is to provide a method for preparing concrete in concrete mixers, the method being comparatively simple yet effective and to provide an apparatus for practicing the method, the apparatus itself being comparatively inexpensive to manufacture and apply to a concrete mixer.

Still a further object is to provide means for effectively discharging all of the cement and aggregate or concrete from various receptacles of the concrete mixer, namely the skip and the mixing drum thereof.

Still a further object is to provide a method for preparing concrete which contemplates the imparting of "vibrations" to the skip and the mixing drum of a concrete mixer, such vibrations being imparted only when the skip is in discharging position and only when concrete is being prepared in or discharged from the mixing drum.

In this connection, the imparting of vibrations or the energizing of a vibrator which is attached to the skip or the mixing drum is one of the primary features of my invention. I am aware that heretofore blows have been imparted to skips and mixing drums, such blows being mechanically produced in various ways. The application of a vibrator to the skip and one to the mixing drum, however, produces a construction in which the skip and mixing drum are actually vibrated so as to vibrate the coating of cement especially, which tends to stick to the surfaces of the skip and drum and thus loosen them during the discharging process of the skip into the drum and from the interior surfaces of the drum during the preparation of the concrete, or while discharging into a chute leading from the drum.

Still a further object is to provide an apparatus in which vibrators are applied to the skip and mixing drum of a concrete mixer with novel means being provided for energizing the vibrators during preparation or discharging periods.

With these and other objects in view, my invention consists in the steps of the process herein-after outlined and in the construction, arrangement and combination of the various parts of the apparatus, whereby the objects contemplated are attained, as hereinafter more fully set forth, pointed out in my claims and illustrated in the accompanying drawings, in which the apparatus is disclosed.

On the drawings, Figure 1 is a plan view of a concrete mixer with my apparatus applied thereto for practicing the process which I will disclose.

Figure 2 is a side elevation of the same, some

parts being broken away to better illustrate the invention.

Figure 3 is a side elevation with parts of the mixing drum and skip broken away and shown in section to illustrate the vibrators applied to the concrete mixer in accordance with my invention.

Figure 4 is an enlarged sectional view on the line 4—4 of Figure 3 showing a collector ring arrangement.

Figure 5 is a side elevation similar to a part of Figure 2 showing a modified construction in which pneumatically operated rather than electrically operated vibrator means is used.

Figure 6 is an enlarged sectional view on the line 6—6 of Figure 5 showing the pneumatic vibrator.

Figure 7 is an enlarged sectional view on the line 7—7 of Figure 5 showing an automatic air connection for the pneumatic vibrator; and

Figure 8 is a diagram of electric connections of the apparatus.

On the accompanying drawings, I have shown a concrete mixer A more or less diagrammatically since the details thereof do not form any part of my present invention and in fact, do not affect it except as parts of the mixer are described in detail and given reference numerals hereinafter. The concrete mixer A is ordinarily provided with a mixing drum 10 of rotatable character and having mixing blades 12 therein whereby rotation of the drum will tumble and mix cement and aggregate for forming concrete thereof.

Pivoted on a shaft 14, is an arm 16 to the outer end of which is secured a skip 18 to receive cement and aggregate. The skip is adapted to be swung to the dotted line position of Figure 2 for dumping the cement and aggregate into the drum 10.

Within the skip there is provided a compartment 20 in which mixing blades 22 operate to hydrate cement, or in other words, to mix cement and water before introducing such hydrated cement into the mixing drum 10 along with aggregate in the major portion of the skip 18.

A discharge chute 24 is provided for hydrated cement, the lower end being closed by a plate 26. The plate 26 has an extension 28 adapted to engage the mixing drum 10 or any desired projection and open the plate 26 so that the hydrated cement can flow into the mixing drum 10.

Ordinarily in the operation of concrete mixers, the concrete, or especially the cement therein, has a tendency to stick to the skip 18 even when it is in its upstanding discharging position shown by dotted lines in Figure 2. Successive batches

of concrete build up successive coatings of the cement until the coating is quite heavy and during one of the discharging operations of the skip, it discharges into the mixing drum. This makes 5 that particular batch of concrete richer than the others because of the additional cement and the other batches are deficient because of this cement having been taken from them in building up the coating on the surface of the skip.

10 Likewise, coatings are built up in the drum 10 and occasionally break loose making an extra rich and unevenly mixed batch, especially if the cement breaks loose just before discharging the concrete from the mixing drum.

15 Such uneven mixtures of cement are detrimental to the quality of a slab of concrete being laid and especially when the coating from the skip and the coating from the mixing drum combine in a single batch of concrete, an exceptionally rich batch is produced which is proportionally much richer than the ordinary run of batches. All of this is undesirable and I have found that by 20 the use of vibrators as I will describe, these difficulties are overcome and all batches of concrete from the mixer are uniform.

25 I have also devised a means whereby the mixture is more uniform throughout, such means consisting of the hydrator, indicated by the reference numerals 20, 22, 24, 26 and 28, which is attached to the skip and accordingly vibrated with the skip to effectively expel all the hydrated cement therefrom during a skip dumping operation.

30 In Figures 1, 2 and 3, I have shown a vibrator B for the skip 18. The vibrator B may consist of a motor 30 having an off-center weight 32 on the shaft thereof whereby rotation of the motor shaft will produce vibration because of the unbalanced centrifugal force of the eccentric weight 32 during rotation thereof.

35 10 It is not necessary to vibrate the skip 18 except when it is in discharging position. I provide means for automatically energizing the motor 30 at only the discharging position of the skip, such means consisting of a stationary contact 34 on 40 the frame of the mixer A and a movable contact 36 engageable therewith. The contact 36 is mounted on the skip 18 and suitably insulated relative thereto. The contacts 34 and 36 are in one side of the electric circuit, as shown in Figure 8, the other side being grounded through the machine to the motor 30.

45 When the skip 18 is raised to discharging position, the contact 36 enters the contact prongs 34, thus establishing the electric circuit to cause vibration of the skip 18.

50 60 This vibration is not to be confused with hammering which knocks the cement loose, vibration, on the other hand, being imparted to the skip for causing it to vibrate and thus free the coating of cement therefrom due to the inertia of the coating tending to cause it to remain in one position while the vibration of the skip tends to move it with the vibratory movement. This causes a loosening of the coating and causes it to flow more freely into 65 the mixing drum 10 while the vibrator is operating.

65 70 The plate 26 for the hydrated cement is moved to open position, as shown by dotted lines in Figure 3, when the skip is in discharging position. This prevents the hydrated cement from flowing from the chute 24 before the skip is in position for it to flow into the mixing drum. The discharge end of the chute 24 is quite small so as to reduce the flow of the hydrated cement sufficiently to cause flow thereof into the mixing drum

during three or four rotations of the drum. This evenly distributes the hydrated cement throughout the aggregate flowing into the drum from the skip.

75 The vibrator B being attached to the skip 18 also vibrates the container for the hydrated cement so as to effectively discharge it completely instead of leaving any coating for subsequent accidental discharge into later batches of concrete with the consequent unevenness of quality throughout the batches.

80 For the mixing drum 10, I provide a vibrator C consisting of a motor 38 and an eccentric weight 40. These are housed in a housing 42 secured by struts 44 or the like to the interior or exterior of the mixing drum 10.

85 A collector ring assembly D is shown in Figure 4. Where one side of the motor 38 is grounded, it is merely necessary to provide a contact 48 for conducting electricity to the motor. Where a two wire system is used, a collector ring 50 is also provided with which a stationary contact 52 coacts. The contacts 48 and 52 may be carbon brushes spring pressed to maintain good contact as illustrated in Figure 4.

90 Means in the form of a push button 54 is provided for automatically operating or energizing the vibrator C. The push button 54 is located so that a projection 56 of a discharge chute 58 is engageable therewith when the discharge chute is in discharging position. Thus only when concrete is being discharged from the drum 10 the vibrator C operates, should its operation be unnecessary in the intervening periods of time.

95 Sometimes it is necessary to have the vibrator C operate in the intervening periods of time because there is a tendency for the concrete to build up a film on the drum in excess of that which can be vibrated loose during the discharging periods only. I have therefore provided a switch 55a which shunts the switch 54 and thus causes continuous operation of the vibrator C. After the excessive film of concrete has been removed, then the switch 55a can be opened whereafter automatic operation of the vibrator C will occur only during the discharging periods or when the chute 58 is in discharging position.

100 The push button 54 is connected with a conduit 57 which in turn, through the medium of an outlet box 55, is connected with a conduit 53. The conduit 53 leads to the collector ring assembly D. A conduit 59 is provided for convenience in connecting the electric system of the vibrators A and B to a source of current supply.

105 In Figures 5, 6 and 7, I have shown a pneumatic vibrator B'. It is designed to take the place of the vibrator B and comprises a cylinder 61 having a reciprocable piston 60 therein. This is of the ordinary pneumatic hammer type and the parts are so designed that the piston 60 reciprocates rapidly within the cylinder 61 to produce vibrations.

110 The ordinary means for energizing the vibrator B' may consist of a compressed air supply pipe 62 having a head 64 to coact with a head 66 of a pipe 68. The pipe 68 and the head 66 are carried by the skip 18 while the head 64 is mounted stationarily. In the skip discharging position, the head 66 enters the head 64 as shown in Figure 7 and engages a sealing cup leather 70 against the action of a spring 72. At the same time a valve 74 is automatically opened for admitting compressed air to the vibrator B' and thereby

operating it. The valve 74 is automatically re-closed when the head 66 is withdrawn from the head 64.

A vibrator C' of similar construction to the one shown in Figure 6 may be mounted in the drum 10 and connected by a rotary air tight connection D' and a conduit 53a with a valve 54a. Compressed air is supplied to the valve 54a from a conduit 59a. The valve 54a corresponds to the switch 54 and is normally closed but opened upon engagement of the projection 56 of the chute 58 therewith. If it is desired to continuously operate the vibrator C', a valve 54b may be opened for continuously supplying compressed air thereto rather than supplying it only when the valve 54a is opened.

I have shown two forms of vibrators, one operated by electricity and another by compressed air. These or other types of devices which will impart actual vibrations to the skip and mixing drum may be used in practicing my process. Steps of the process may be changed and changes in the construction and arrangement of the parts of the apparatus may be made without departing from the real spirit and purpose of my invention. Therefore, I intend to cover by my claims such modified methods and forms of structure or mechanical equivalents which may be reasonably included within their scope.

30 I claim as my invention:

1. An apparatus for preparing concrete comprising a mixing drum, a skip movable from a supine receiving position to an upstanding discharging position, an electrically operated high frequency vibrator attached to said skip and adapted when energized to vibrate said skip sufficiently to render its contents flowable therefrom and circuit closing means operable by said skip to energize said vibrator when said skip is in discharging position.

2. An apparatus for preparing concrete comprising a mixing drum, a skip movable from a supine receiving position to an upstanding discharging position, a pneumatically operated high frequency vibrator on said skip and adapted when operable to vibrate said skip to render its contents flowable therefrom and valve means operable by said skip to energize said pneumatic vibrator when said skip is in discharging position.

0 3. An apparatus for preparing concrete comprising a mixing drum, a movable discharge chute therefor, a vibrator on said drum, means engaged by said discharge chute when in discharging position to operate said vibrator to cause flowability of concrete in said drum and

means to render said last means ineffective and to continuously operate said vibrator.

4. An apparatus for preparing concrete comprising a mixing drum, a movable discharge chute therefor, an electrically operated high frequency 5 vibrator on said mixing drum and circuit closing means operable by said discharge chute to energize said vibrator either continuously or when said discharge chute is in discharging position to cause flowability of concrete in said drum. 10

5. An apparatus for preparing concrete comprising a mixing drum, a movable discharge chute therefor, a pneumatically operated high frequency vibrator on said mixing drum and valve means operable by said discharge chute to energize said vibrator when said discharge chute is in discharging position to cause flowability of concrete in said drum. 15

6. An apparatus for preparing concrete comprising a mixing drum, a skip movable from a supine receiving position to an upstanding discharging position, a vibrator on said skip, a vibrator on said mixing drum, means energized by said skip when moved to discharging position to operate the vibrator thereon at a frequency 25 sufficiently high enough to cause flowability of concrete in said skip and means to operate the vibrator on said mixing drum to cause flowability of concrete in said drum.

7. An apparatus for preparing concrete comprising a mixing drum, a skip movable from receiving position to discharging position relative to said mixing drum, an electrically operated high frequency vibrator on said skip, an electrically operated high frequency vibrator on said mixing 30 drum, circuit closing means operable by said skip to energize said vibrator on said skip when said skip is in discharging position to cause flowability of concrete in said skip and circuit closing means operable to energize said vibrator on said mixing 35 drum to cause flowability of concrete in said drum.

8. An apparatus for preparing concrete comprising a mixing drum, a skip movable from receiving position to discharging position relative 45 to said mixing drum, a pneumatically operated high frequency vibrator on said skip, a pneumatically operated high frequency vibrator on said mixing drum, valve means operable by said skip to energize said vibrator on said skip when it is 50 in discharging position to cause flowability of concrete in said skip and valve means operable to energize said vibrator on said mixing drum to cause flowability of concrete in said drum.

ROBERT B. GAGE. 55
